(Roswell Miller)

Letters Patent (Patented April 19, 1826)

The Schedule referred to in these Letters Patent, and making part of the same, containing a description in the words of the said Roswell Miller himself of his improvement, being a conical water-wheel.

This wheel stands in a perpendicular position, and contains the principles of action and reaction. The form of the wheel is conical and may be inclined in any scale of degrees, so as to preserve the conic shape. A slope of forty five degrees, however, is considered the most judicious inclination of the plane. The shaft enters into the top of this cone and hangs on a pivot at the bottom. On this cone are fixed buckets, from four to 12 inches wide, which are placed on the edge and bound diagonal by round wedges, commencing near the top at an angle of about 45 degrees and gradually making the angle more acute as they descend the cone till they . . . . and parallel to the circle of the wheel. This scale of degrees, may be increased or diminished, to any degree within 45° but the manner described is conceived to be the best.

The number of buckets must depend upon the head of water required power &c. and may be from 8 to 14. These buckets are closely crowded from one end to the other, so as to confine the water between them. The wheel sits in the floor of the frame or foundation. This floor approaches to the mouth of the wheel on a level with it, as close as possible, without obstructing its operation. A circular rack or screen (which also is so constructed as to direct the water against the face of the buckets as herein after described) is then made around the mouth of the wheel so near as merely to admit a thin gate between the screen and the mouth of the wheel as herein after mentioned. The slats of this rack or screen are made of thin planks from four to six inches wide on an angle of about 11.3° .

goes from the centre which will direct the water immediately against the face of the buckets ^{in the mouth} of the wheel and gives it the first motion. The gate is like a slide descending the shaft and shuts down between the wheel and the mouth of the wheel, or on the outside of the sack, the former method however is thought most advisable.
